UNITED STATES PATENT OFFICE

171,122

ICE CREAM CUP

Madeleine L. Conlin, Locust Valley, N. Y.

Application September 28, 1953, Serial No. 26,970

Term of patent 7 years

(Cl. D8—1)

To all whom it may concern:

Be it known that I, Madeleine L. Conlin, a citizen of the United States of America, residing at Locust Valley, L. I., in the county of Nassau and State of New York, have invented a new, original, and ornamental Design for an Ice Cream Cup, of which the following is a specification, reference being had to the accompanying drawing, forming part thereof.

The single drawing figure is a perspective view of an ice cream cup, showing my new design.

The side of the cup not shown presents a substantially similar appearance as the side disclosed.

I claim:

The ornamental design for an ice cream cup, substantially as shown and described.

MADELEINE L. CONLIN.
